UNITED STATES PATENT OFFICE.

CHARLES C. KENYON, OF RARITAN, NEW JERSEY, ASSIGNOR OF ONE-HALF
TO DAVID R. KENYON, OF SAME PLACE.

PIECE-WASHING MACHINE.

SPECIFICATION forming part of Letters Patent No. 662,377, dated November 20, 1900.

Application filed August 2, 1900. Serial No. 25,699. (No model.)

To all whom it may concern:

Be it known that I, CHARLES C. KENYON, a citizen of the United States, and a resident of Raritan, New Jersey, have invented certain Improvements in Washing-Machines for Textile Fabrics, of which the following is a specification.

The object of my invention is to so construct a washing-machine for textile fabrics that the fabric will be rubbed before passing to the wringing-rolls.

The machine to which my improvement is applied is a machine for washing a continuous strip or a series of continuous strips of textile fabric.

In the accompanying drawings, Figure 1 is a longitudinal sectional view of my improved washing-machine; and Fig. 2 is a sectional view on the line 2 2, Fig. 1.

20 A A are the frames of the machine, connected together by suitable bolts, and between the frames is a tub or wash-box B, having a rounded bottom and closed at each end.

25 Mounted in bearings in the frames A A are the rolls C C'. These rolls are the wringing or squeezing rolls of the machine and are geared together by long tooth-gears. One of the rolls is adjustable in respect to the other, so that more or less pressure can be given to 30 the goods as they pass between the rolls.

35 Directly in front of the rolls C C' are the rubbing-rolls D D'. These rubbing-rolls are longitudinally reciprocated as they are turned, so as to give a rubbing action to the cloth as it passes between them. The rolls have spindles d at each end, mounted in bearings E E'. The bearings E slide in guideways E' at each side of the frame, and springs e tend to force the roll D' toward the roll D, 40 and above the springs e are set-screws e', so that the pressure can be regulated as desired.

On the spindle d of each roll are cams d'. In the present instance on each bearing is a bracket d², having a roller or pin d³, which enters the slot in the cam, so that as the shafts are turned the cams cause each roll to move longitudinally. The cams are so set that one will move longitudinally in one direction while the other is moving longitudinally in 50 the opposite direction.

The rolls D D' are geared together by long-

toothed gear-wheels, so as to allow for a certain amount of yield of the upper roll, and they are driven from the main shaft by a chain, belt, or other suitable mechanism, the 55 belt passing around a sprocket-wheel on the main shaft and around a sprocket-wheel on the spindle of either the roll D or the roll D'.

Directly in front of the rolls D D' is a plate or board F, having a series of eyelets f acting as guides through which the fabric passes to the rubbing-rolls, and in front of the board or plate F is a guide-roll G, over which the fabric passes from the vat to the eyelets.

At the back of the rolls C C' is a guide-roll 65 G', having longitudinal ribs. This roll directs the fabric that passes from the rolls C C' into the tub or wash-box. The ends of the fabric introduced into this machine are secured together, so as to form a continuous 70 piece, and there are any number of these pieces, according to the capacity or width of the machine.

It will be seen that the fabric is first submerged in the wash-water, then carried over 75 the roll G through one of the eyelets in the board F between the rubbing-rolls D D', and rubbed not only to thoroughly cleanse the fabric, but also to change the lay of the goods, so that the goods will not become creased by 80 continuous pressing in the same position.

The fabric as it comes from the rubbing-rolls passes between the squeeze or wringing rolls C C', then over the guide-roll G', and into the vat again. By placing the rubbing-rolls so 85 that the fabric, which is continuous, will pass from the vat between the rubbing-rolls, then between the pressing or wringing rolls, and again into the vat I am enabled to thoroughly cleanse the fabric and at the same 90 time rearrange the folds. Directly under the rubbing-rolls and the squeeze-rolls is a trough B', into which the water or other liquid

squeezed from the fabric by the rolls D D' and C C' is collected. This trough has a stopper at the bottom, so that the liquid can either be held in the trough so as to flow out at one side clear of the machine or simply pass into the lower wash-box, or by removing the plug the liquid can pass into the wash-box again. 95 During the first washing I simply allow the liquid squeezed from the fabric to pass into 100

the wash-box again; but at the close of the operation I prefer to collect the dirty liquid and pass it off to one side and allow fresh liquid to enter the box, so that by this means 5 I may rinse the fabric prior to its removal from the machine, so that the fabric is thoroughly washed and rinsed and the goods are not creased to such an extent that the folds cannot be obliterated when the fabric under- 10 goes final treatment.

I claim as my invention—

1. The combination in a machine for washing fabrics, of a wash-box, a pair of squeeze-rolls mounted above the box, means for driving the squeeze-rolls, and a pair of rubbing-rolls mounted on one side of the squeeze-rolls, means for driving the said rolls, means for reciprocating one or both of the rolls, and guides for the fabric, the whole being constructed so that the fabric will pass from the wash-box between the rolls and into the box again, substantially as described. 15 20

2. The combination of a wash-box, a pair of squeeze-rolls mounted above the box, means 25 for driving said squeeze-rolls, a pair of rub-

bing-rolls mounted on one side of the squeeze-rolls, cams for longitudinally reciprocating the said rubbing-rolls, means for revolving the rolls, guides in front of the rubbing-rolls so that the continuous fabric will pass from the wash-box, between the rubbing-rolls and then between the squeeze-rolls, and again into the box, substantially as described. 30

3. The combination in a fabric-washing machine, of a wash-box, a pair of squeeze-rolls mounted above the box, means for driving the said squeeze-rolls, a pair of rubbing-rolls mounted on one side of the squeeze-rolls, means for rotating said rubbing-rolls, means for reciprocating each roll, guides for the fabric, and a collecting-trough for the liquid mounted directly under the rubbing and squeeze rolls, substantially as described. 35 40

In testimony whereof I have signed my name to this specification in the presence of two subscribing witnesses. 45
